CLAIM

We claim the ornamental design for a workwall assembly, as shown.

DESCRIPTION

FIG. 1 is a perspective view of a workwall assembly;
 FIG. 2 is a front elevational view of the workwall assembly;
 FIG. 3 is a rear elevational view of the workwall assembly;
 FIG. 4 is a side elevational view of the workwall assembly, the opposite side being a mirror image thereof;
 FIG. 5 is a top plan view of the workwall assembly; and,
 FIG. 6 is a bottom plan view of the workwall assembly.
 The dashed lines and broken lines are for purposes of illustrating environmental structure and form no part of the claimed design.
